L. A. KREJCI

MULTIPLE JACK AND SWITCH

Filed April 20, 1925

UNITED STATES PATENT OFFICE.

LADDIE ALOIS KREJCI, OF CHICAGO, ILLINOIS, ASSIGNOR OF ONE-THIRD TO CHARLES J. NORRE AND ONE-THIRD TO CARL G. ROLIN, BOTH OF CHICAGO, ILLINOIS.

MULTIPLE JACK AND SWITCH.

Application filed April 20, 1925. Serial No. 24,678.

To all whom it may concern:

Be it known that I, LADDIE ALOIS KREJCI, a citizen of the United States, and a resident of Chicago, in the county of Cook and State of Illinois, have invented a new and useful Improvement in Multiple Jacks and Switches, of which the following is a full, clear, and exact description.

My invention relates to improvements in multiple jack and switch of the type employed particularly in radio circuits, and it consists in the combination, constructions, and arrangements herein described and claimed.

15 An object of my invention is to provide in a single unit a novel combination of filament and plate circuit switches, together with a plug and jack.

A further object of my invention is to 20 provide a device of the character described in which the filament switches and plate circuit switches are operated simultaneously by movement of the plug when disposed in an operative position in engagement with 25 the jack.

A further object of my invention is to provide a device of the character described in which operation of the switches cannot be carried out unless the plug is in proper 30 engagement with the jack.

A further object of my invention is to provide a device of the character described which is simple in construction, extremely compact in form, and thoroughly practical 35 for the purposes intended.

Other objects and advantages will appear in the following specification, and the novel features of the invention will be particularly pointed out in the appended claims.

40 My invention is illustrated in the accompanying drawings, forming part of this application, in which—

Figure 1 is a side elevation of an embodiment of my invention,

45 Figure 2 is a sectional view along the line 2—2 of Figure 1,

Figure 3 is a sectional view along the line 3—3 of Figure 1,

50 Figure 4 is a sectional view along the line 4—4 of Figure 1,

Figure 5 is a sectional view along the line 5—5 of Figure 1,

Figure 6 is a sectional view along the line 6—6 of Figure 1, and

Figure 7 is a side elevation of a part of 55 the device illustrated in Figure 1.

In carrying out my invention I make use of a hollow substantially cylindrical body member 1 preferably of molded composition. This body member is provided with a cover 60 plate 2 also of molded composition and the entire casing so formed is adapted for mounting upon an instrument panel 3 as by the provision of screws 4.

A rotor 5 also of molded composition is 65 rotatably disposed within the casing by the provision of trunnions 6 and 7 respectively, forming an integral part of cam members 70 8 and 9 respectively, which are insulated from one another and disposed at the opposite ends of the rotor. The trunnion 7 is tubular and forms one terminal of my improved jack. I shall hereinafter refer to this member 7 as the jack sleeve. The 75 jack sleeve being integral with the cam member 9 is therefore electrically connected therewith.

The cam member 8 has a contact member 80 10 associated therewith in axial alignment with the jack sleeve 7. This contact member forms the opposite terminal of the jack.

In Figure 1, in dotted lines, I have shown a standard jack plug 11 having a terminal 12 arranged for projection through the jack sleeve 7 and therefore for electrical connection therewith, and a terminal 13 arranged for connection with the contact member 10 and for electrical connection therewith.

With reference to Figure 7, it will be 90 noted that the rotor 5 has an irregularly shaped filament switch contact plate 14 disposed upon the peripheral wall of the rotor. Contact fingers 15, 16, 17 and 18 respectively are mounted upon the casing 1 and are 95 projected through the walls of the casing so as to lie in engagement with the rotor 5 and in engagement with the plate 14 selectively as the rotor is turned.

The fingers 15 and 16 are in longitudinal 100 alignment with one another. The fingers 17 and 18 are spaced laterally from one another so as to engage with different portions throughout the width of the plate 14.

With reference to Figures 3, 4 and 5, it 105 will be noted that when the rotor 4 is in the position shown that none of the fingers 15, 16, 17 or 18 are electrically connected with

one another. When the rotor is rotated 60°, the fingers 15 and 16 will be electrically connected by means of the plate.

Further rotation of the rotor to the extent 5 of an additional 120° will cause the plate to move in engagement with the finger 17, while still in engagement with the fingers 15 and 16. Still further rotation of the rotor another 120° will cause the plate to move into 10 engagement with the finger 18 while still in engagement with the fingers 17, 16 and 15. Further rotation of the rotor in the same direction 60° will disconnect all the fingers from the plate 14 and the fingers and rotor 15 will lie in the same position as when at the start as is shown in Figures 3, 4 and 5. It will be noted that the description of the rotation of the rotor as here given is in a clockwise direction.

20 The fingers 15, 16, 17 and 18 and the plate 14 comprise what is known as the filament switch of my improved multiple jack and switch and is for the purpose of operating at will, selectively, one, two or three vacuum 25 tubes in the radio circuit with which my improved device is employed and which circuit is illustrated in Figure 8.

The cam member 8 is adapted to engage 30 during the rotation of the rotor 5 described selectively, with three switch blades 19, 20 and 21 respectively, constructed of resilient material. The switch blades 19, 20 and 21 contact with the rotor 8 selectively simultaneous with the engagement of the plate 14 35 with the fingers 15-16, 17 and 18 respectively.

Each of the switch blades 19 and 20 is 40 provided with a combined contact and stop member 22 and 23 respectively with which the switch blades engage when the cam member is not in engagement therewith. The switch blade 21 has a stop member 24 similar in construction to the contact and stop members 22 and 23 with the exception that 45 there is no means for connecting the member 24 with an electrical circuit. The stop members 22 and 23 as well as the switch blades 19, 20 and 21 have integral ears 25 extending exteriorly of the casing 1 by means of 50 which the members may be connected with an electrical circuit. In like manner each of the fingers 15, 16, 17 and 18 have ears 25 formed integral therewith for connecting the fingers with an electrical circuit.

55 Three resilient switch blades 26, 27, and 28 are provided for the cam member 9. These blades are identical in construction with the blades 19, 20 and 21, and are disposed in the same relationship with the 60 cam member 9 as are the blades 19, 20 and 21 and the cam 8. Each of the blades 26 and 27 have combined contact and stop members 28 and 29 respectively. The blade 28 has a stop member 30 identical to the stop 65 member 24. All the switch blades and con-

tact stop members have ears 25 for electrically connecting the members to an electrical circuit.

In Figure 7, I have shown a view of the rotor 5 from which it will be noted that the 70 trunnion 7 or jack sleeve has a recess 31 extending longitudinally thereof from the end of the sleeve. A pin 32 (see Figure 1) supported upon the body of the plug 11 is adapted for projection into the recess 31 75 when the plug is inserted in the jack, thus rotation of the plug must occasion rotation of the rotor 5.

From the foregoing description of the various parts of the device, the operation 80 thereof may be readily understood. In operation the operator will project the plug into the jack as shown in Figure 1, and rotate the rotor 5 by rotation of the jack 11 to the position shown in dotted lines in Figures 2 85 and 6, i. e., 60°. This will cause the cams 8 and 8 to engage with the blades 19 and 26 respectively, and to disconnect these blades from their stop contacts 22 and 28 respectively. At the same time the plate 14 will 90 engage with and electrically connect the fingers 15 and 16 to operate the filament 40 in the tube 35.

The cams 8 and 9 are electrically connected by means of the contact 10 and the 95 jack sleeve 7 with the terminals 13 and 12 of the plug 11 respectively.

If it is now desired to operate a different part of a radio circuit (not shown) the detector and the first amplifier stage, the jack 100 is rotated an additional 120°. This will cause the plate 14 on the rotor to engage with the finger 17 while still in engagement with the fingers 15 and 16. The cams 8 and 9 will move out of engagement with the blades 19 and 26 and these blades will then contact their contact stop members 22 and 28 respectively.

The cams at this time will engage with the blades 20 and 27 respectively to move the blades out of engagement with their stop contacts 23 and 29 respectively, and to electrically connect the plug 11 with the blades 20 and 27 through the terminals 13 and 12 110 respectively of the plug.

Further rotation of the rotor an additional 120° will bring still another part of the circuit into play.

I claim:

1. A multiple jack and switch of the 120 character described, comprising a casing of insulating material adapted for mounting upon an instrument panel, a rotor rotatably mounted within said casing, a jack sleeve disposed on the axis of said rotor and partially projecting through said casing, a plug contact member carried by said rotor, contact members mounted on said rotor and electrically connected with said jack sleeve and said plug contact member, switch blades 125 130

carried by said casing and being arranged for engagement with certain of said contact members selectively on said rotor as said rotor is rotated, an additional contact member carried by said rotor, and additional switch blades carried by said casing and adapted to engage with the additional contact member of said rotor, whereby a filament circuit may be opened and closed by 10 the rotation of said rotor.

2. A multiple jack and switch of the character described, comprising a casing of insulating material adapted for mounting upon an instrument panel, a rotor rotatably mounted within said casing, a jack sleeve disposed on the axis of said rotor and partially projecting through said casing, a plug contact member carried by said rotor, contact members mounted on said rotor and 20 electrically connected with said jack sleeve and said plug contact member, switch blades carried by said casing and being arranged for engagement with certain of said contact members selectively on said rotor as said 25 rotor is rotated, an additional contact member carried by said rotor, additional switch blades carried by said casing and adapted to engage with the additional contact member of said rotor, whereby a plurality of circuits 30 may be opened and closed at will, and a plug

adapted for engagement with said contact sleeve and said plug contact member.

3. A multiple jack and switch of the character described, comprising a casing of insulating material adapted for mounting upon an instrument panel, a rotor rotatably mounted within said casing, a jack sleeve disposed on the axis of said rotor and partially projecting through said casing, a plug contact member carried by said rotor, contact members mounted on said rotor and electrically connected with said jack sleeve and said plug contact member, switch blades carried by said casing and being arranged for engagement with certain of said contact members selectively on said rotor as said rotor is rotated, an additional contact member carried by said rotor, additional switch blades carried by said casing and adapted to engage with the additional contact member of said rotor, whereby a plurality of circuits may be opened and closed at will, and a plug adapted for engagement with said jack sleeve and said plug contact member, said plug and said jack sleeve being constructed so as to interlock, whereby the rotation of said plug will occasion the rotation of said rotor.

LADDIE ALOIS KREJCI.
